UNITED STATES PATENT OFFICE.

FRANK H. HEITGER, OF INDIANAPOLIS, INDIANA.

CARBURETER.

1,000,209.

Specification of Letters Patent. Patented Mar. 17, 1914.

Application filed June 8, 1912. Serial No. 702,616.

To all whom it may concern:-

Be it known that I, FRANK H. HEITGER, a citizen of the United States, residing at Indianapolis, Marion county, and State of Indiana, have invented and discovered certain new and useful Improvements in Carbureters, of which the following is a specification.

My said invention consists in certain improvements in the details of construction of carbureters, relating especially to carbureters having glass float chambers, and it consists in means whereby such chambers may be used and attached to the mixing chamber, interchangeably with metal chambers and at the same time provide for a radially adjustable gasoline feed attachment, all as will be hereinafter more fully described and claimed.

Referring to the accompanying drawings, which are made a part hereof and on which similar reference characters indicate similar parts; Figure 1 is a side elevation of a carbureter embodying my said invention, and Fig. 2 a central vertical section through the same.

In said drawings the portions marked A represent the mixing chamber, B the gasoline reservoir or float chamber, C an annular casing member, or top, interposed between said float chamber and said mixing chamber, and D the main air supply inlet.

The general construction of said carbureter is or may be substantially that of the well-known Heitger carbureter, which is illustrated herein, or any other form found appropriate.

The valve 40 for controlling the auxiliary air inlet is mounted on a spring 41 arranged to be regulated and operated as more clearly explained in my companion application No. 702,612.

The mixing chamber A is formed with a central depending suction tube 10 having the gasoline and air inlet fitting 12 on the lower end thereof, in which is mounted the spray nozzle 13.

The float chamber consists of a glass bowl B supported by nut 14 on the lower end of a screw-threaded shank 15 depending from the casting 12. The inner end of the hot air supply tube D is interposed between said nut and the lower end of said bowl, a gasket 16 forming a tight joint between them. A gasoline inlet x and air inlets z are provided in casting 12, as is usual.

The annular casing member or top C carrying the gasoline supply connection C¹ is formed of metal and interposed between the chamber A and the upper edge of chamber B, a gasket 17 being interposed in an annular recess between the adjacent edges of said part.

As will be readily seen, the loosening of nut 14 permits ring C to be turned to bring the inlet C¹ to any side of the carbureter or to any position most convenient to the gasoline supply.

The float 20 is connected to one end of a pivoted lever 21, which operates valve 22, which controls the flow of gasoline through channel 23 from the supply tank to the reservoir, or float chamber, B in the well known manner.

What I claim is-

1. A carbureter comprising a casing containing a mixing chamber and a carbureting chamber extending from one side thereof, a metal ring carrying the gasoline supply connection mounted to surround said carbureting chamber and seat on one side upon an appropriate seat formed on said casing, a glass float chamber also surrounding said carbureting chamber and formed to seat at its upper edge against said ring, a metal supply tube mounted on the lower end of said float chamber, said carbureting chamber being provided with a part adapted to extend through said tube and formed screw-threaded, and a nut on said screw-threaded end adapted to secure and clamp said several parts together, whereby they may be adjusted circumferentially independently of each other, substantially as set forth. 75

2. A carbureter comprising a metal mixing chamber, a glass float chamber and a metal ring carrying the gasoline supply connection and interposed between said glass float chamber and metal mixing chamber and supported to be adjusted circumferentially, substantially as set forth. 95

3. A carbureter comprising a metal mixing chamber, a circumferentially adjustable metal ring on the under side of said mixing chamber, a gasoline supply attachment connected with said ring, a glass float chamber adjacent to the lower edge of said ring and a clamping nut connected with a central screw-threaded shank extending through said parts and adapted to secure them all together, substantially as set forth. 105

4. A carbureter comprising a carbureting

and mixing chamber formed with a main and an auxiliary air inlet, an air supply tube mounted at the base of said carbureting chamber and adjacent the main air inlet capable of circumferential adjustment, a float chamber surrounding said carbureting chamber and mounted adjacent said air supply tube, and a ring carrying the fuel supply to said float chamber mounted between 5 said mixing chamber and said float chamber, 10

and circumferentially adjustable therebetween, substantially as set forth.

In witness whereof, I have hereunto set my hand and seal at Indianapolis, Indiana, this 21st day of May, A. D. nineteen hundred and twelve.

FRANK H. HEITGER. [L. S.]
